United States Patent Office

Des. 182,999
Patented June 10, 1958

182,999

HAT

Marvin I. Glass, Chicago, Ill.

Application December 12, 1957, Serial No. 48,871

Term of patent 14 years

(Cl. D3—13)

Fig. 1.

Fig. 2.

Fig. 3.

Figure 1 is a side elevational view of a hat showing my new design;

Figure 2 is a top plan view thereof; and

Figure 3 is a front elevational view thereof.

The dominant features of my design are shown in solid lines.

I claim:

The ornamental design for a hat, substantially as shown and described.
